(57) **CLAIM**

The ornamental design for an air freshener device, as shown.

DESCRIPTION

FIG. 1 is perspective view of an air freshener device embodying the present invention;

FIG. 2 is a front view of the air freshener device;

FIG. 3 is a rear view of the air freshener device;

FIG. 4 is a side view of the air freshener device;

FIG. 5 is an opposite side view of the air freshener device;

FIG. 6 is a plan view of the air freshener device; and,

FIG. 7 is a bottom view of the air freshener device.
